Charles Morgan

Letter Patent

The subscriber referred to in these Letters Patent and making part of the same containing a description in the words of the said Charles Morgan, inventor of his improvement in the process for preserving timber and all kinds of wood.

The stems of timber wood when a short time, must be coated for the purpose of insuring preservation by holding the quantity of the various timber so prepared. The timber when coated as above is then placed in the eastern the largest pieces being in layers and placed before, from the other one side or more until the bottom side to be clear, but on this unless from the bottom. The plank to put in at the same time they must occupy the uppermost layer and be placed in ridge. In virtue of my process there may be many timber as required should we ever be deficient from so filled with same or other water to add water all the timber previously to be dried, a vehicle and a sufficient quantity of fresh water quickly turn to saturated the water, a few and each earthen pot of water will be sufficient. The top of the eastern being of course a top of the water will be dry by it absorption, vehicle, must be replaced from time to time with fresh water as the eastern must always be kept full. The same process can must also obtain in respect to the stems. The eastern will being attracted from the atmosphere by the stems, will form a thin crust or vehicle of the moisture of time on the surface of the stems, which after a time will be precipitated and replaced by another crust or vehicle which will be precipitated until finally all the stems in the eastern will become changed into a crust which is said to consist usually of fresh water, very few minutes. This is the opinion of the subscriber and in about year he says that all kinds of wood when so prepared from one to four weeks will be perfectly preserved in this way so it is easy to see that months and that longer time such as long of facts, more water is to be added also in the process to completely saturated in from the first time.

Charles Morgan thinks from his own observation on this experiment that wood prepared in this way will remain sound and free from any decay whatever, in any case it might respect to timber twice so perhaps

even a longer time than it would otherwise have or last, because it might be. The same principle also obtains in the use of a composition as a cement or mask of equal parts of lime, ashes of wood stalk and thistles reduced to a proper consistency with water and applied as a mask to a single side board three coats of which will be sufficient to protect the wood from decay many years longer than it would otherwise and longer also than paint and oil would preserve it. This is a new and certain fact in the destructive destruction of any kind of wood and it is obtained from known of the nature of ligninous acid which in reality is the acetic acid contained with the purest animal oil and bitumen. The acetic acid readily unites with all the alkalies and most of the earths.

This it is that the lime in the form of a hydrate, finally, neutralizes the wood acid forming an acetate of lime, by which chemical combination, the power of vegetable decomposition and destruction to the wood is thus prevented for a great length of time. Windows may be protected the same way as doors or any other object.
